(57) **CLAIM**

The ornamental design for a heat pump dispenser, as shown and described.

DESCRIPTION

FIG. 1 is a perspective view of a heat pump dispenser;
FIG. 2 is another perspective view thereof;
FIG. 3 is a right side elevation view thereof;
FIG. 4 is a left side elevation view thereof;
FIG. 5 is a front elevation view thereof;
FIG. 6 is a rear elevation view thereof;
FIG. 7 is a top plan view thereof; and,
FIG. 8 is a bottom plan view thereof.

The broken lines in the drawings depict portions of the heat pump dispenser that form no part of the claimed design.
